UNITED STATES PATENT OFFICE.

BONIFACIO MONTANTE, OF SAN LUIS POTOSI, MEXICO.

SUPPLEMENTAL OUTSOLE FOR SHOES.

Application filed October 31, 1923. Serial No. 671,913.

This invention has relation to footwear and has particular reference to a supplemental out-sole for shoes the principal object of which is to protect the regular out-sole of the shoe against wear for the purpose of increasing the length of the life of the shoe and preserve the shape and appearance of the shoe by eliminating the necessity of re-soling the same.

10 As a further object the invention aims to provide a supplemental out-sole for shoes which will more effectively operate to exclude or prevent the entrance of dampness or moisture through the sole of the shoe 15 while at the same time serving to cushion the tread surface.

As a still further object the invention aims to provide a supplemental out-sole for shoes which will afford means for preventing slip-20 page and will give a better traction when walking or running.

The invention furthermore contemplates a supplemental out-sole for shoes which is extremely simple in its construction, inexpensive to manufacture and which may be readily applied or removed from the out-25 sole of the shoe without the service of a skilled shoe maker or mechanic.

With the above recited and other objects 30 in view, the invention resides in the novel construction set forth in the following specification, particularly pointed out in the appended claim and illustrated in the accompanying drawing, it being understood that the right is reserved to embodiments other than those actually illustrated herein to the 35 full extent indicated by the general meaning of the terms in which the claim is expressed.

In the drawing—

40 Figure 1 is a bottom plan view of a sole constructed in accordance with the invention.

Fig. 2 is an edge view thereof.

45 Fig. 3 is an edge view of a pair of soles illustrating the manner in which the same are associated for transportation and sale.

Fig. 4 is a bottom plan view of a shoe with the supplemental out-sole in applied position.

50 Fig. 5 is a fragmentary cross sectional view therethrough taken approximately on the line 5—5 of Fig. 4.

55 Referring to the drawing by characters of reference the supplemental out-sole consists of an inner layer of fabric 10 which is preferably rubberized canvas and an outer

tread layer 11 of vulcanized rubber which is so secured or attached to the inner layer as to form an integral part thereof. The outer surface of the outer or tread layer 11 is preferably formed with suitable ribs or other embossed portions 12 to provide a traction or non-slip surface. In practice the supplemental out-sole is preferably formed slightly larger than the particular size of sole to 60 which it is to be applied whereby the edges thereof may be trimmed down after its application to the out-sole of the shoe to give or lend to the shoe a neat appearance. The supplemental out-sole is of an appropriate 65 size to cover the entire out-sole of the shoe from the juncture of the shank thereof with the front of the heel to the toe and the shank portion 13 of said supplemental out-sole is 70 preferably of lesser thickness than the ball 75 or tread portion.

In applying the supplemental sole to the regular out-sole indicated at A in Fig. 5, the surface of the out-sole A is filed or sand papered until a rough, but clean, surface is 80 provided. In shoes which are provided with channelled stitching the channel flap is removed by cutting or filing away. A thin coat of cement indicated by the character 85 14 in Fig. 5, is then applied to the sole of the shoe, which, after ten minutes drying or setting is then re-coated with a second coat of cement which is allowed to dry or set for an appropriate length of time. The exposed 90 face of the fabric or inner layer 10 is then coated with cement, which, after drying or setting a sufficient length of time is pressed into contact with the out-sole A of the shoe, care being taken that pressure is exerted 95 over the entire sole to firmly unite the supplemental sole with the sole A of the shoe. After setting for a sufficient length of time, a sharp knife is employed to cut away the remaining edges of the supplemental sole 100 in order that the edges thereof are flush and conform to the edges of the sole A. As an additional protection and securing means, a small arcuate metallic plate 15 is screwed, nailed or otherwise fastened and anchored by suitable fastening means 16 to the toe 105 of the shoe, said fastening means 16 passing through the supplemental sole and anchored into the sole A. When the supplemental sole is worn through, it may be readily removed by the use of gasoline or other solvent material for dissolving the cement 14. In storing, shipping and selling a pair of 110

supplemental soles including right and left soles the members are arranged with the inner faces of the canvas layers 10 disposed toward each other with a separator strip 17 interposed therebetween to prevent adherence of the faces to each other, which faces are more or less sticky or adhesive.

I claim:

As a new article of manufacture, a pair 10 of supplemental out-soles adapted to be applied to a pair of shoes for maintaining the shape of the shoe and preventing the en-

trance of dampness through the sole, said pair of supplemental out-soles each consisting of an inner layer of rubberized canvas 15 and an outer tread layer of vulcanized rubber secured to the inner layer to form an integral part thereof, the said pair of soles having adhesive inner faces on the inner layers thereof, and a strip of separator material interposed therebetween permitting of ready separation of the pair of soles for application.

BONIFACIO MONTANTE.
